(57) **CLAIM**

The ornamental design for a personal care implement handle, as shown and described.

DESCRIPTION

FIG. 1 is a top perspective view of a personal care implement handle showing my new design;

FIG. 2 is a top plan view thereof;

FIG. 3 is a bottom plan view thereof;

FIG. 4 is a left side elevational view thereof, the right side elevational view being the mirror image thereof;

FIG. 5 is a front elevational view thereof;

FIG. 6 is a rear elevational view thereof;

FIG. 7 is a top perspective view of a modified form of a personal care implement handle showing my new design;

FIG. 8 is a top plan view of FIG. 7;

FIG. 9 is a bottom plan view of FIG. 7;

FIG. 10 is a left side elevational view of FIG. 7, the right side elevatioal view being the mirror image thereof;

FIG. 11 is a front elevational view of FIG. 7; and,

FIG. 12 is a rear elevational view of FIG. 7.

The broken lines showing a bristle support, bristles, and pumice stone in FIGS. 1-12 and the supporting opening in FIGS. 7-9 and 12 are included for the purpose of showing environmental structure that forms no part of the claimed design.
